UNITED STATES PATENT OFFICE.

SALVATORE SPINA AND ALBERT COOK, OF NEW YORK, N. Y.

VENDING MACHINE.

Application filed December 23, 1927. Serial No. 242,048.

This invention relates to vending machines, and more particularly relates to a machine for the automatic vending of newspapers, magazines and stacked articles in general upon the insertion of a coin, including means for preventing the ejection or removal of more than a predetermined quantity of the material vended after each operation of the machine.

Machines heretofore constructed for the vending of articles and for the vending of newspapers and magazines especially have generally been complicated, unsatisfactory in operation and too expensive to make them commercially practical to install. Machines and devices now in use, on the other hand, which have not been beyond the reach of commercial adaptation have been generally unreliable in operation, not "fool proof", easily become disarranged or out of order, and not sufficiently sturdy to long withstand the rough usage which such machines must undergo.

An object of our invention is to provide a machine which is commercially practicable and positive and certain in its operation.

Another object of our invention is to provide a machine which is substantially "fool proof" and sufficiently sturdy to meet the demands of long continued and hard usage.

Still another object of our invention is to provide a machine which reliably operates upon the insertion of a coin and which positively prevents the ejection or removal of more than a predetermined quantity of the article vended.

Another object of our invention is to provide a machine which can be constructed at reasonable cost, which can be commercially adapted with profit, and which will answer all the exigencies of the trade.

Other objects of our invention will become evident as the disclosure proceeds.

In order that a clearer understanding of our invention may be had, attention is hereby directed to the accompanying drawings, forming a part of this application and illustrating certain possible embodiments of our invention.

Referring to the drawings:

Fig. 1 is a front elevation of our machine with the major portion of the front panel broken away;

Fig. 2 is a side elevation of our machine with the side panel removed and is taken on line 2—2 of Fig. 1;

Fig. 3 is a top elevation of our machine with the top panel removed and is taken on line 3—3 of Fig. 1; and

Fig. 4 is an internal vertical cross-sectional view showing a portion of the operating mechanism and is taken on line 4—4 of Fig. 1.

Similar reference characters refer to similar parts throughout the several views of the drawings and the specification.

Referring to the drawings, the machine generally comprises an outer casing 1 of suitable shape, comprising side walls 2 and 3, top wall 4 and front wall 5, which houses articles to be vended and the operative mechanism.

A magazine 6 of proper shape and size to accommodate the stacked articles is suspended or affixed to the upper portion of the casing.

The magazine 6 may, if desired, be provided with adjustable sides to accommodate various sized articles. A pair of rollers 7 and 8 are horizontally disposed near the bottom of the magazine and are pivoted for rotation to the side walls of the casing.

It is understood that the stacked articles disposed in the magazine are supported by the rollers 7 and 8. Each roller has a gear wheel 9 and 10 secured to an end thereof adapted to rotate with the rollers.

The rollers are operatively connected by connecting gear 11, so that they both rotate in unison and in the same direction.

A crank handle 12 or other suitable means disposed on the outside of the casing is attached to the projecting shaft 13 of one of the rollers operative to rotate the rollers for a purpose hereafter to be described.

A suitable coin control mechanism represented in its entirety by numeral 14 is attached to the interior of the casing and receives the coin from coin slot 15. A suitable chute or guideway 16 conducts the coin to a receiving pan portion 17 of locking lever 18 frictionally pivoted to bracket 19 at 20 attached to a side of the casing.

The locking lever has a deformed portion 21 overlapping one end of roller 7 projecting beyond the side wall of the magazine 6. A plurality of pins 22 (eight being shown in the drawings) are firmly affixed to and along the periphery of the roller.

Locking ears 23 projecting from deformed portion at the end thereof are adapted to drop between and engage one or more of the pins 22. In normal position it is seen that the locking lever is in the position

illustrated by full lines in Fig. 2, the coin receiving pan being disposed at the mouth of

the roller. Locking ears 23 projecting from deformed portion at the end thereof are adapted to drop between and engage one or more of the pins 22. In normal position it is seen that the locking lever is in the position

illustrated by full lines in Fig. 2, the coin receiving pan being disposed at the mouth of

the roller. Locking ears 23 projecting from deformed portion at the end thereof are adapted to drop between and engage one or more of the pins 22. In normal position it is seen that the locking lever is in the position

the chute, and the locking ears engaging one or more of the pins 22, thereby locking the rollers from rotation in either direction.

When the proper coin is dropped into the slot 15, it descends the chute and strikes the receiving pan 17. The force of the impact causes the pan to descend, raising the other end of lever 18 from locking engagement with the rollers. The edge of the receiving pan 17, after descending a distance sufficient to adequately clear the locking end of the lever from engagement with the pins 22 on the roller 7, strikes coin receiving funnel 24, causing the coin to slide off the receiving pan 15 through the funnel and into the coin box 25. The locking lever then assumes the position shown in dotted lines in Fig. 2.

An inclined shelf 26 horizontally disposed has its ends secured to the sides of the casing 20 with its upper edge approximately on a level with the rollers and its lower edge adjacent the delivery mouth or opening 27 in the casing. The article vended, it is understood, passes from the rollers 7 and 8 across the shelf 25 26 and out through the delivery opening 27.

A trip lever pivoted at 29 to a suitable standard 30 has an upturned arm portion 31, whose upper end 32 is normally seated in a slot 33 cut in the edge of the shelf 26. The 30 projecting arm of the trip lever is positioned approximately at the midsection of the magazine for a purpose hereafter to be described. The other arm 28 of the trip lever balances the upturned arm portion 31 of the lever so that 35 the upturned portion is normally seated in the slot as above described, and shown in dotted lines in Fig. 4. Arm 28 has a bent portion 35 leading to and projecting under the pan receiving end of locking lever 18.

Now it is seen that as the vended article 40 passes over the inclined shelf, the edge of the vended article strikes the projecting end 32 of upturned arm 31, causing it to rotate about pivot 29 until it assumes the position shown 45 in full lines in Fig. 4. The bent portion 35 of the weighted arm 28 during this pivoting operation raises the pan receiving end of locking lever 18 back to normal position, moving the ears 23 into locking engagement 50 with the next succeeding pin, preventing further rotation of the rollers. As soon as the projected article is removed, the upturned arm drops back into its slot position.

The rollers are preferably surfaced with 55 a soft rubber composition 36, either having vacuum cups or ridges in its periphery to positively grip the lowermost article placed in the magazine, moving it forwardly to the inclined shelf. A sliding and adjustable gate 60 37 having an outturned guide flange portion 38 may be adjustably secured to the outside front wall of the magazine by means of which the opening between the lower end of the magazine and the forward roller 8 can be varied and adjusted, to accommodate va-

rious thicknesses of articles to be vended. The opening can be thus adjusted so as to be only sufficiently large to permit the proper and predetermined quantity of vended articles to be emitted from the magazine.

The top wall 4 of the casing may be removable or hinged, permitting access to the magazine for charging purposes and adjustment of the mechanism. The front wall 5 of the casing may be wholly or partly composed 75 of glass or transparent material, if desired, as well as the front wall of the magazine 6, so that the number of articles contained and the operation of the machine may be observed. The exterior of the casing may carry 80 advertising matter or may be otherwise attractively decorated.

The operation of the machine is as follows:—A coin dropped into the coin slot 15 passes through the coin control mechanism 14 through the chute 16 and onto the receiving pan 17. The impact, as heretofore stated, forces the pan end of the lever 18 downwardly, raising the locking end of the lever out of engagement with pins 22 and the roller 7, in which position it is sustained by friction or other suitable means at pivot 20, the coin then sliding into the coin box 25. Crank 12 can then be turned, operating the rollers, which grasp the lowermost article contained 95 in the magazine and move it forwardly onto the shelf 26, gate 37 having been properly adjusted to permit only the predetermined amount or number of articles to pass out upon the shelf. As the article slides over the shelf, end 32 of upturned arm 31 is engaged by the article and swung outwardly, the article proceeding out of the delivery opening 27, where it can be removed. The bent portion 35 of the weighted arm 34 during the pivoting 100 movement engages and raises the pan end of lever 18 and places the ears 23 on the other end thereof into position for locking engagement with one of the pins 22. The machine is now ready to receive a second coin and to repeat the operation.

Although the machine above described is especially adapted to vending newspapers, leaflets and magazines, it is readily apparent that the machine is adapted to operate upon other articles in accordance with and under our invention herein disclosed. It is further understood that all matter contained in the above description or shown in the accompanying drawings shall be interpreted as illustrative and not in a limiting sense.

What we claim is:—

1. In a vending machine, in combination, a magazine for stacked articles, rollers at the bottom of said magazine, means for rotating said rollers, coin controlled means normally locking said rollers against rotation, including a pivoted lever having one end in normal locking engagement with one of said rollers and its other end adapted to receive a coin 130

whereupon said lever is moved from locking engagement with said roller, and a pivoted trip lever having an end in engageable contact with said locking means and having an upturned portion adapted to be depressed by the vended article to restore the said locking means in locking engagement with said rollers.

2. In a vending machine, in combination, a magazine for stacked articles, rollers at the bottom of said magazine, means for rotating said rollers, coin controlled means normally locking said rollers against rotation, an inclined shelf having its higher edge at the level of said rollers and its lower edge extending to the delivery mouth of the machine, a slot in said shelf, and a pivoted trip lever having one end in engageable contact with said locking means and having an upturned portion at its other end projecting through said slot in the inclined shelf, said upturned portion adapted to be depressed by the vended article to restore said locking means to locking engagement with said rollers.

3. A vending machine, including in combination, a casing, a magazine for stacked articles within said casing, a pair of rollers operably connected at the bottom of said magazine, means for rotating said rollers, coin controlled means normally locking said rollers against rotation, including a pivoted lever having one end in normal locking engagement with one of said rollers and its other end adapted to receive a coin whereupon said lever is moved from locking engagement with said roller, an inclined shelf extending to the delivery mouth of said cas-

ing, a centrally disposed slot in said shelf, and trip mechanism having an upturned portion projecting through said slot adapted to be depressed by the vended article to restore said locking means to locking engagement with said rollers.

4. A vending machine, including in combination, a casing, a magazine for stacked articles within said casing, a pair of rollers operably connected at the bottom of said magazine, means for rotating said rollers, coin controlled means normally locking said rollers against rotation, including a pivoted lever having one end in normal locking engagement with one of said rollers and its other end adapted to receive a coin whereupon said lever is moved from locking engagement with said roller upon insertion of a coin, an inclined shelf having its higher edge at the level of said rollers and its lower edge extending to the delivery mouth of said casing, a centrally disposed slot in said shelf, and trip mechanism operable to restore said locking means to locking engagement with said rollers upon the ejection of a predetermined quantity of said stacked articles, said trip mechanism including a pivoted lever having one end in engageable contact with one end of said locking lever and its other end provided with an upturned portion extending through said slot and adapted to be depressed by the vended article as it leaves the machine.

This specification signed this 21st day of December, 1927.

SALVATORE SPINA.
ALBERT COOK.
